(57) **CLAIM**

The ornamental design for a fluid container, as shown and described.

DESCRIPTION

FIG. 1 is a front perspective view of a fluid container embodying my new design, which has a lid attached to a container vessel;

FIG. 2 is a rear perspective view thereof;

FIG. 3 is a front perspective view thereof, with the lid of the fluid container in an open position;

FIG. 4 is a rear perspective view thereof;

FIG. 5 is a front elevation view of the fluid container of FIG. 1;

FIG. 6 is a right elevation view thereof;

FIG. 7 is a rear elevation view thereof;

FIG. 8 is a top plan view thereof; and,

FIG. 9 is a bottom plan view thereof.

The broken lines show portions of the fluid container that form no part of the claimed design.

The shading lines only help to show the shape and do not depict any surface decoration.
